UNITED STATES PATENT OFFICE.

CURTIS L. CRUVER, OF CHICAGO, ILLINOIS.

DESIGN FOR A DOUBLE TOP.

No. 39,757.

Specification for Design.

Patented Jan. 12, 1909.

Application filed September 14, 1908. Serial No. 453,053. Term of patent 3½ years.

To all whom it may concern:

Be it known that I, CURTIS L. CRUVER, a citizen of the United States, residing at Chicago, in the county of Cook and State of Illinois, have invented a new, original, and ornamental Design for a Double Top, of which the following is a specification, reference being had to the accompanying drawing, forming a part thereof.

Figure 1 is a side elevation of a double top, showing my new design. Fig. 2 is a top plan view.

The double top comprises two hollow substantially frusto-conical parts 1 secured together at 2. The exterior or concave face of each of the parts 1 is ornamented as shown in Fig. 1.

I claim:

The ornamental design for a double top, as shown and described.

CURTIS L. CRUVER.
